UNITED STATES PATENT OFFICE.

NICKOLAS E. BROWN, OF MARION, SOUTH DAKOTA.

TABLE.

No. 847,899.

Specification of Letters Patent.

Patented March 19, 1907.

Application filed May 23, 1905. Serial No. 261,835.

To all whom it may concern:

Be it known that I, NICKOLAS E. BROWN, a citizen of the United States, residing at Marion, in the county of Turner and State of 5 South Dakota, have invented new and useful Improvements in Tables, of which the following is a specification.

The invention relates to an improvement in tables, and particularly a self-waiting table, wherein a part of the table is adapted 10 for movement relative to a fixed portion.

The main object of the present invention is to revolvably mount the central portion of 15 the table and also adapt the same for vertical adjustment, whereby said central portion may be revolved at any desired height to present any required point thereof in the desired relation to the fixed section of the table.

20 The invention in its preferred form will be described in the following specification, reference being had particularly to the accompanying drawings, wherein—

25 Figure 1 is a plan view of my improved table. Fig. 2 is an elevation of the same, and Fig. 3 an enlarged sectional detail illustrating the adjusting means for the movable section.

30 Referring to the drawings, my improved table constructed of any material desired is preferably circular in plan, the top comprising two sections, a fixed section 1 and a movable section 2. As shown, the movable section is arranged centrally of the fixed section, the latter being concentric with the movable 35 section and essentially comprising an annular rim or leaf surrounding the movable section. It is understood that the joint between the movable section and fixed section is so arranged that when the sections are arranged in the same horizontal plane they 40 present practically an unbroken surface.

45 The table—that is, the fixed section—is supported upon legs 3 in any desired manner, one of which, as 4, is arranged centrally of the table. At the upper end the leg 4 is formed with a transverse slot 5 and with a vertically-arranged opening 6, extending lengthwise of the leg to the desired distance and communicating at its upper end with the 50 slot 5. The movable section 2 is supported upon a stem 7, depending centrally therefrom and connected at its lower end with a rod 8, formed with a series of circumferentially-arranged teeth 9, suitably spaced apart 55 and formed to project their opposite faces in

a downward direction. Angle-dogs 10, pivotally mounted at 11 within the slot 5 near opposite ends thereof, are arranged to project their operative ends 12 in position to engage the teeth 9 on the bar 8. The dogs are provided with arms 13, terminally connected through the medium of a spring 14 with one of the walls of the slot 5. The dogs are so arranged with their free terminals of the arms 13 under the influence of the springs 14 normally projecting beyond the plane of the leg 4, as clearly shown in Figs. 2 and 3, whereby said dogs may be operated to release the rod 8, and thereby adjust the movable section. For convenience in operation the 60 movable section is provided with a series of peripherally-arranged knobs 15, by which the movable section may be conveniently turned on its axis, as will be evident.

In use the movable section may be freely 65 elevated to the desired height by an upward pull on the same, as the teeth 9 are arranged to freely pass the dogs 10 in the upward movement of the movable section. When the section has reached the desired height, 70 the dogs will engage beneath the properly-situated tooth 9 and prevent a downward movement of the section 2. Owing to the circumferential arrangement of the teeth 9, the movable section 2 may be freely revolved 75 on the rod 8 without disengaging the dogs 10 therefrom. When it is desired to return the movable sections to a normal position, the projecting ends of the arms 13 of the dogs are forced inward to the plane of the leg, thereby 80 disengaging the operative ends of the dogs from the teeth 8 and permitting the movable section to move downward to the desired extent or to the complete normal position.

In the above-described construction it is 85 to be particularly noted that I combine with a materially-reduced engaging end of each dog an upwardly-projecting operating-arm, whereby the dogs are released by a downward movement of the said engaging ends, 90 this movement being normally counteracted by the springs. This construction materially facilitates the adjustment of the table, as the weight of the table tends to move the dogs into disengaging position, counteracted only 95 by the pressure of the springs.

The table described is particularly useful in ordinary meal service, as it enables the users to revolve the movable section carrying the food in bulk to bring any article of food 100

within convenient reach, the knobs 15 serving as effective handholds for the movement of the table.

Having thus described the invention, what I claim as new is—

A table comprising a fixed section having a central leg formed with a longitudinally-arranged opening and with diametrically-opposed recesses communicating with the opening, a movable section concentric with the fixed section and having a depending stem of smooth exterior, a rod terminally connected to the stem and snugly fitting within the longitudinally - arranged opening in the leg, said rod being formed with a series of circumferentially-arranged teeth, dogs pivotally mounted in the recesses on opposite sides of the rod, said dogs comprising normally horizontal members and arms projecting upwardly from the ends thereof and at an incline thereto, the upper surface of the members being normally horizontal and being

adapted to bear beneath the horizontally-projected surface of any of said teeth, the lower edges of the members being arranged at an incline to the edge thereof and terminating coincident with the free end of said upper edge, whereby to provide a pointed end for the members to avoid frictional bearing against the sides of the teeth, springs secured within the recesses and bearing against the arms of the dogs to normally force said arms to maintain locking position of the horizontal members, the upward projection of the arms of the dogs serving to permit disengagement of said dogs by a downward movement of the horizontal members, thereby facilitating the adjustment of the table.

In testimony whereof I affix my signature in presence of two witnesses.

NICKOLAS E. BROWN.
